METHOD AND APPARATUS FOR TRANSFORMING BENDABLE MATERIAL INTO PREDETERMINED AND FINISHED SHAPES

Durward K. Hopkins, Peoria, Ill., assignor to Keystone Steel & Wire Company, Peoria, Ill., a corporation of Illinois

Application July 1, 1935, Serial No. 29,214

41 Claims. (Cl. 140—71)

This invention has reference to a method and apparatus for transforming bendable lengths of material, such as wire, into predetermined and finished shapes, such for instance, as garment hangers having the usual trouser support or hanger body, coat arms, and a hook by which the same may be suspended from a suitable support.

That the invention may be more fully understood, reference is had to the accompanying drawings forming a part of this description, illustrating a preferred embodiment of the invention, in which:

Fig. 1 is a side elevation of an apparatus embodying my invention, suitable for the carrying out of my improved method, certain parts thereof being broken away, the dotted lines shown therein indicating operative positions assumed by certain of said forming mechanisms and associated parts;

Fig. 2 is an enlarged detail view in perspective, partly in section, of one of the former elements and its support;

Fig. 3 is a top plan view of the apparatus illustrated in Fig. 1;

Fig. 4 illustrates a finished wire shape in the form of a garment hanger produced by employing my improved method and apparatus;

Fig. 5 is a sectional view of welded portions of the hanger taken on the line 5—5 of Fig. 4;

Fig. 6 is a fragmentary top plan view illustrating in enlarged detail the welding gripping jaws and associated parts in open adjustment preparatory to a welding operation;

Fig. 7 is a view similar to Fig. 6 illustrating said mechanism in closed adjustment for a welding operation;

Fig. 8 is an enlarged sectional view of a portion of the actuating mechanism for one of the welding gripping jaws as the same would appear if taken on the line 8—8 of Fig. 6;

Fig. 9 is an end elevation, partly in section, illustrating the movable support and formers carried thereby, and associated parts, having assembled therewith for illustrative purposes a garment hanger shown in dotted lines; as the same would appear if taken on the lines 9—9 of Fig. 3;

Fig. 10 is a fragmentary end elevation, partly in section, of the stationary support, mandrel and associated parts, having the formers illustrated in Fig. 9, shown in dotted line association with said support and mandrel, as the same would appear if taken on the line 10—10 of Fig. 3;

Fig. 11 is a fragmentary sectional view taken on the line 11—11 of Fig. 10;

Fig. 12 is an enlarged sectional view in elevation, taken on the line 12—12 of Fig. 3, certain parts broken away, illustrating the wire feeding rolls, wire loading and cutting chamber and associated parts, the associated forming mandrel shown in dotted lines;

Fig. 13 is a sectional view of the wire loading chamber taken on the line 13—13 of Fig. 12, one of the former elements shown in dotted lines preparatory to acting upon a length of wire, and a wire shown in dotted lines deposited on the forming mandrel, said mandrel and associated support likewise shown in dotted lines;

Fig. 14 is an end elevation of the ratchet feeding device for said wire loading chamber, parts thereof shown in dotted lines, as the same would appear if taken on the line 14—14 of Fig. 12;

Figs. 15 to 24, both inclusive, illustrate diagrammatically the steps and elements successively taken and utilized to transform a length of wire into a predetermined and finished wire shape, such as a garment hanger of the type illustrated in Fig. 4.

Like characters of reference denote corresponding parts throughout the figures.

To a full and complete understanding of the use of my improved method and apparatus, reference will be first made to the wire shape to be produced. In Fig. 4 there is shown a wire shape in finished form as produced thereby, known as a garment hanger. The apparatus produces said hanger shapes in inverted form as shown finished in said figure and comprises the base or trouser support A, the side or coat arms B and the hook portion C by which the hanger may be suspended from a suitable support. The neck portion D thereof is a welded structure, however, it is apparent that this securing may vary in nature in accordance with the wishes of the manufacturer and demands of the trade and be therefore accomplished in many different ways, such for instance, as by twisting of the wires.

In the drawings, 1 designates a bed frame supported at the ends by legs or standards 2. A table 3 is slidably mounted on said bed frame 1 and is adapted to be reciprocated towards and away from one end of said frame by means of a pitman bar 4, one end of which is connected to 50 the underneath forward end of said table at 5, the other end of said pitman having connection to a driving wheel 6 at 7. The wheel 6 is mounted upon a shaft 8, the latter supported by the bearing housings 9 from said bed frame 1 and being 55

driven by the driving pulley wheel 10 which receives its power from a driving belt 11 or from any other suitable source.

Suitably secured to the forward end of said table 3 is an upright member 12 braced thereon by the brace pieces 13 at the inner ends thereof and is adapted to travel reciprocally with the movement of said table 3. The upper central portion of said member 12, see Fig. 9, is shown provided 10 with a substantial opening 14 of a size having width and depth to permit the passage therethrough of a finished wire shape, such as a garment hanger shown in dotted lines in said figure. On the exterior face of said member 12 in association with said opening 14 are fixedly mounted 15 a series of horizontally disposed shaper elements or formers comprising duplicate formers 15, 15, one each located at the upper opposite ends of said opening 14 and consisting of a U-shaped 20 elongated member, see Fig. 2, the forward end of which is flattened and pointed as at 16 and cut away therefrom to provide a cam-like acting surface 17. 18, 18 designate other duplicate formers, one each located below the formers 15, 15 in association with said opening 14 consisting of a 25 blade-like member and having its forward end diagonally shaped as at 19 to provide a cam-like acting surface. 20, 20 designate a further duplicate set of formers similar to the formers 18, 18 and are adapted to be located only a short distance therefrom in relation to the opening 14 and each have a like forward acting surface 21. The formers 18, 18 and 20, 20 are substantial duplicates of each other, however, their respective 30 lengths are slightly less than the formers 15, 15 for the reason that they perform their respective functions subsequent to the functions of the longer formers 15, 15 which are initially acting formers. 22, 22 designate a further duplicate set of formers similar in length to the formers 20, 20, however, their forward ends are shown to have an 35 arcuately shaped acting surface 23, best shown in Figs. 3 and 22. Said formers 22, 22 are preferably adapted to be connected to a companion former 20, 20 either by being made integral therewith or by welding and disposed substantially at the angles shown in Fig. 9, whereby the forward ends of the arcuately shaped acting surfaces 23, 23 merge into the diagonal shaped forward acting surfaces 21, 21 of the formers 20, 20. 40 50 55 60 65 70 75

24 designates a relatively short final shaper element or former constructed similarly to the formers 15, 15, the forward end of which is flattened and pointed as at 25 and cut away therefrom to provide a cam-like acting surface 26, best seen in Figs. 1, 6 and 7, however shown in Figs. 3, 9, 22, 23 and 24. 27 designates a single former, see Figs. 3, 9 and 16, likewise associated with the opening 14 and located preferably medially of the formers 15, 15 on said member 12. Said former 27 is preferably of the same length as the formers 15, 15, see Fig. 3, and the forward acting end thereof is diagonally shaped to provide the cam-like surface 28, see Fig. 18.

Across the forward end of the bed frame 1 of said apparatus, an upright plate member or support 29 is secured thereto by suitable fastening means 30. 31 designates oppositely disposed braces whereby said plate member 29 is reinforced against the thrusts and strains imposed incident to the shaping operations.

As shown in Fig. 10, the plate member or support 29 is provided with a series of suitably shaped openings located therein in axial alignment with said series of shaper elements or form-

ers carried by the upright member 12, whereby when said member and formers are caused to travel towards said plate member 29, said formers will pass through their respective openings in said member 29 and assume the dotted line positions shown in said figure, including Figs. 1 and 3. 32 designates a mandrel suitably provided or secured to the inner face of the plate member or support 29 having a contour representing the substantial outline configuration to be given to the article to be made, in this case, a garment hanger, and the mandrel is so disposed on said member 29 and in relation to the openings therein, just referred to, that certain of the reciprocally acting shaper elements or formers will cooperate with certain of the outline edges of said mandrel, see Fig. 10.

Referring now to Figs. 3, 10 and 12, a wire feeding, cutting and loading device is shown which is supported across the top of the plate member 29 by means of the tubular supports 33. The device comprises a rotatably mounted barrel or chamber 34, the periphery of which is bored to provide spaced grooves or holes 35 throughout the length thereof, the ends being 25 provided with extended shaft portions 36 and 37, the former received within a journal mounting 38 and the latter within a similar mounting 39. Referring more particularly to Fig. 10, the barrel 34 is shown to be reduced in diameter whereby to accommodate therebeneath the reciprocal travel of the shaper elements or formers 15, 15 and 27. A tubular housing 40 is encased about the barrel or chamber 34 whereby to normally retain the lengths of wires received within the holes 35 therein. Referring to Figs. 10, 12 and 13, the housing 40 is likewise cut away to register with the reduced diameter portions of the barrel or chamber 34 so as to permit the passage of the shaper elements or formers 15, 15 and 27. Referring to Figs. 11 and 13, the relative positions of the housing 40 and mandrel 32 are shown, also, the manner in which the housing 40 is provided with a slotted opening 41 overlying said mandrel 32 whereby lengths of wire may be passed 45 through said opening from said barrel and deposited on the mandrel, as shown in dotted lines in Fig. 13.

Reference being had to Fig. 12, the inner end of the journal mounting 38 has suitably secured thereto a hardened steel circular facing 42 which cooperates with a similar facing 43 provided on the barrel 34 which together function to sever the wire into lengths as it is passed through the opening 44 by means of the feeding wheels 45 50 55 60 65 70 75 80 85 90 95 100 105 110 115 120 125 130 135 the holes 35 therein with the slotted opening 41 of said housing 40 and at the same time register one of the holes 35 with the wire feed opening 44 in the journal mounting 38.

5 Referring to Fig. 13, the barrel or chamber 34 is shown as having six (6) holes 35, however, it will be understood that more or less may be provided. As illustrated herein, the barrel 34 contemplates the advance filling or storing of four 10 (4) of such holes 35 whereby a pre-stored amount of predetermined lengths of wire are made ready for feeding into the shaping apparatus. It will be understood that upon the barrel 34 being rotatively advanced to register an empty hole 35 15 with the wire feed hole 44, that the wire supply will be fed forward by the feed wheels 45 and be caused to abut the end face of the journal mounting 39 in said hole, whereupon in the next partial revolution imparted to said barrel, the 20 wire length just inserted will be severed by the cutters 42 and 43 and so on in like sequence. The feed wheels 45 may be caused to operate continuously or intermittently in timed relation to the rotative movement of the barrel 34.

25 The welding gripping jaws, setting and tripping mechanisms therefor and transformers for supplying the welding current is best illustrated in Figs. 1, 3, 6 and 7 and since the jaws, setting and tripping mechanisms are provided in duplicate, the description of one will suffice for the other.

On the interior face of the upright member 12 are secured bracket members 55 preferably insulated therefrom by a non-conductor 56 and 35 having pivotally mounted at one end thereof co-acting welding gripping jaws 57, the forward ends thereof being disposed through the lower portion of the opening 14 in said member 12 and located between the shaping elements or formers 40 22, 22 and 24, see Fig. 9. Wire gripping dies 58 are suitably secured on the inner forward ends of said jaws and are provided with suitable grooves or recesses 59 to securely clamp the wires adapted to be received therein and prevent 45 slippage thereof. The jaws 57 receive the welding current from flexible laminated buss wires 60 which have connection to a transformer 61 shown located on the table 3, the lead in wires thereto designated 62 which may be connected to any 50 suitable source of electrical supply, not shown. The inner ends of the gripping jaws 57 are pivotally connected at 63 to a multiple connection comprising a link 64 and diverging arm 65 connected thereto, the end of which is supplied with an 55 abutting shock face 66 for contacting the end of the adjustable set screw 67 located within a bracket member 68 connected to said upright member 12. The link 64 is pivotally connected at 69 to another short link 70 which is pivotally 60 connected at 71 to an extended portion of the bracket member 55. Referring to Fig. 8, a rod 72 is shown bifurcated at 73 and pivotally connected at 63 together with the gripping jaw 57 and link 64 and is caused to have a sliding fit 65 connection through the extended portion of the bracket member 55 at 74. Between the opening 74 of the member 55 and the outer end of the rod 72 is provided a coiled spring 75 encircling said rod and by means of adjusting nuts 76 on 70 said free end of the rod, the coiled spring may be compressed to provide any suitable tension needed depending upon the operating requirements. The diverging arms 65 have pivotally connected thereto at 77 arms 78 which are adapt- 75 ed to travel through and be supported by bracket

arms 79 fixedly secured to the bed frame 1 at 80, said arms 79 being reinforced by the supporting standards 81. The free ends of the arms 78 are threaded to receive adjusting nuts 82 whereby to adjust their contacting the bracket arms 79 and cause the tripping of the arms 65 to close the gripping jaws 57 into the position shown in Fig. 7. In the length of said arms 78, preferably near the pivotal point 77, said arms are threaded to receive adjusting nuts 83 which are adapted to contact the opposite face of said bracket arms 79 and cause the setting of said gripping jaws into opened position, as shown in Fig. 6. In Fig. 1, there is shown a depending switch actuating arm 84 suitably connected to the upright member 12, the lower end of which is adapted to engage the operative portion or button 85 of a relay switch 86 shown connected to the forward end of the bed-frame 1. The source of electrical current for the relay switch is not shown, however, it will be understood that when said switch is actuated by contact from the arm 84 that the transformer 61 will be energized for a limited period of time to furnish the dies 58 of the jaws 57 with welding current. 25

In the operation of the tripping and setting mechanisms for the welding jaws, it will appear obvious that upon the table 3 being moved from the full line position to the dotted line position shown in Fig. 1, that the adjusting nuts 82 will 30 be caused to abut the stationary bracket arms 79, thereby pulling the diverging arms 65 from the position shown in Fig. 6 to that illustrated in Fig. 7 which breaks, so to speak the straight line connection of the links 64 and 70 and allows the coiled springs 75 to urge the rods 72 inwardly causing the jaws 57 to pivot and bringing the dies 58 into clamping or closed position, as shown in Fig. 7. The released rearward movement of the arms 65 is checked by the set screws 67. It 40 is preferred that at the moment of releasing the opened gripping jaws 57 to closed position that the actuating arm 84 will likewise be caused to operate the button 85 of the relay switch and thereby cause the transformer 61 to deliver for 45 only a very short period a welding current to the dies 58 of the jaws 57. Upon the return movement of the table 3 from the dotted line position to the full line position shown in Fig. 1, it will be further understood that the adjusting nuts 83 50 will be caused to abut the stationary bracket arms 79, thereby forcing the diverging arms 65 backwardly from the position shown in Fig. 7 to that shown in Fig. 6, whereby the links 64 and 70 are reset and causing the rods 72 to advance inwardly toward each other compressing the coiled springs 75 and separating the gripping jaws 57 into open position, as shown in Fig. 6. 55

Assuming the barrel or chamber 34 is pre-loaded with cut lengths of wire of the type diagrammatically illustrated in Fig. 15 and further assuming the apparatus is put into operation from the full-line position illustrated in Figs. 1 and 3, it will be understood that the driving wheel 6 and pitman bar 4 will cause the table 3, upright member 12 and associated shaping elements or formers to advance axially towards the upright plate member or support 29, whereupon the extreme forward acting surfaces of the longer formers 15, 27 and 15 will engage the lower exposed wire length, see Fig. 13, and cause the same to be ejected through the slotted opening 41 and deposited upon the upper surface of the mandrel 32. Due to the cam-like acting surfaces 17 of the U-shaped formers 15, 15 the continued 70 75

forward movement thereof deflects or diverts the free ends of the wire length transversely of said formers downwardly around the mandrel in the fashion illustrated in Figs. 16 and 17. The function of the single former 21 is similar in action and snugly maintains the upper portion of the wire length in fitting engagement with the outline or curvature of said portion of the mandrel. The step illustrated in Fig. 16 represents the extent and completion of the work performed by the formers 15, 21 and 15. In the continued forward movement of the former elements, the formers 18 and 20 are brought into play, see Figs. 19 and 20, which cause the free end portions of the wire length to be further likewise deflected and be caused to snugly fit the sides of said mandrel 32 whereby to form the side arms of said garment hanger. The step illustrated in Fig. 19 represents the extent and completion of the work performed by the formers 18 and 20. In the continued forward movement of said elements, the arcuate surfaces of said formers 22, 22 are brought into play, see Figs. 21 and 22, which further deflects the end portions of the wire length towards the base of said mandrel 32 and makes ready one end portion of said wire length to be formed into a hook by the hook forming element or former 24; the continued forward movement of said formers 22, 22, see Fig. 24, simultaneously forming the juxtaposed upstanding neck portions of the hanger, as shown in Fig. 23, and also forming the hook of the garment hanger by means of the following short single former 24 by the cam-like acting surfaces 26 thereof. Preferably during the hook forming step, the dies 58 of the gripping jaws 57 are closed in the manner previously described while the formers 22, 22 are clamping the meeting portions of the wire length to form the neck of the hanger whereupon a welding current is established to weld the neck D, see Fig. 4. At this point the series of formers have reached their forward point of forward travel upon the bed-frame 1 and such position is illustrated in Figs. 1 and 3 in dotted lines. The wire length has been transformed into a predetermined and finished wire shape, namely, a garment hanger.

In the return travel of the table 3, upright member 12 and associated shaping elements or formers from the dotted line position shown in Figs. 1 and 3 to the full line position shown therein, the finished wire shape or garment hanger is removed from association with the mandrel 32 about which it was formed by reason of the clamping jaws and dies 57 and 58 securely clamping the neck portion, the upper looped ends of the hanger being slidably supported on extension rods 87 extending rearwardly of the apparatus from opposite sides of the mandrel 32, see Figs. 1, 3, 9 and 10, upon which the finished shapes or garment hangers are delivered when released from the clamping jaws when opened.

There is an additional advantage in carrying the finished shape or garment hanger with the return movement of the former carrier in that during such movement the welded neck portion is given an opportunity to become fully fused and substantially cooled while said portion is still clamped by the clamping jaws, thereby serving to manufacture a completely welded and strong structure. Upon the clamping jaws being opened in the manner previously described, the former carrier has assumed its most rearward point of travel and this position is represented in full lines

in Figs. 1 and 3, whereupon the finished shape or garment hanger is automatically released and suspended on the extension arms 87 and then pushed manually backwards thereon for the creation of a supply thereof and then manually slid off on the inclined portion of said arms when desired for use.

What I claim is:

1. The method of transforming a length of wire into a predetermined and finished wire shape which consists in initially positioning said length in association with a support, thence subjecting said length to the action of an element comprising a former adapted upon the axial meeting thereof with said support to cause said former to divert said length of wire transversely of said former whereby said length is fashioned to assume final predetermined assemblance and finally securing certain meeting portions thereof to hold the same in finished form. 20

2. The method of transforming a length of wire into a predetermined and finished wire shape which consists in initially positioning said length in association with a support, thence subjecting said length to the action of an element 25 comprising a former adapted upon the axial meeting thereof with said support to cause said former to divert said length of wire transversely of said former whereby said length is fashioned to assume final predetermined assemblance and 30 finally welding certain meeting portions thereof to hold the same in finished form.

3. The method of transforming a length of wire into a predetermined and finished wire shape 35 which consists in initially positioning said length in association with a support, thence subjecting said length to the action of an element comprising a former adapted upon the axial meeting thereof with said support to cause said former to divert said length of wire transversely of said former whereby said length is fashioned to assume final predetermined assemblance, thence securing certain meeting portions thereof to hold the same in finished form and finally discharging the finished shape from said support. 40

4. The method of transforming a length of wire into a predetermined and finished wire shape 50 which consists in initially positioning said length in association with a support, thence subjecting said length to the action of an element comprising a former adapted upon the axial meeting thereof with said support to cause said former to divert said length of wire transversely of said former whereby said length is fashioned to assume final predetermined assemblance, thence 55 welding certain meeting portions thereof to hold the same in finished form and finally discharging the finished shape from said support.

5. The method of transforming a length of wire into a predetermined and finished wire shape 60 which consists in initially positioning said length in association with a support, thence subjecting said length to the action of a movable element comprising a former adapted upon movement axially toward said support to divert said length transversely to the path of travel of said former whereby said length is fashioned to assume final predetermined assemblance and finally securing certain meeting portions thereof to hold the same in finished form. 65

6. The method of transforming a length of wire into a predetermined and finished wire shape 70 which consists in initially positioning said length in association with a support, thence subjecting said length to the action of a movable element 75

comprising a former adapted upon movement axially toward said support to divert said length transversely to the path of travel of said former whereby said length is fashioned to assume final 5 predetermined assemblance and finally welding certain meeting portions thereof to hold the same in finished form.

7. The method of transforming a length of wire into a predetermined and finished wire shape 10 which consists in initially positioning said length in association with a support, thence subjecting said length to the action of a movable element comprising a former adapted upon movement axially toward said support to divert said length 15 transversely to the path of travel of said former whereby said length is fashioned to assume final predetermined assemblance, thence securing certain meeting portions thereof to hold the same in finished form and finally discharging the finished 20 shape from said support upon movement of said former away from said support.

8. The method of transforming a length of wire 25 into a predetermined and finished wire shape which consists in initially positioning said length in association with a support, thence subjecting said length to the action of a movable element comprising a former adapted upon movement axially toward said support to divert said length transversely to the path of travel of said former 30 whereby said length is fashioned to assume final predetermined assemblance, thence welding certain meeting portions thereof to hold the same in finished form and finally discharging the finished 35 shape from said support upon movement of said former away from said support.

9. The method of transforming a length of wire into a predetermined and finished wire shape 40 which consists in initially positioning said length in association with a mandrel, thence subjecting said length to the action of a movable element comprising a former adapted upon movement axially toward said mandrel to divert said length transversely to the path of travel of said former whereby said length is fashioned to assume final 45 predetermined assemblance and finally welding certain meeting portions thereof to hold the same in finished form during movement of said former away from said mandrel.

10. The method of transforming a length of 50 wire into a predetermined and finished wire shape which consists in initially positioning said length in association with a mandrel, thence subjecting said length to the action of a movable element comprising a former adapted upon movement axially toward said mandrel to divert said length transversely to the path of travel of said former whereby said length is fashioned to assume final 55 predetermined assemblance, thence welding certain meeting portions thereof to hold the same in finished form during movement of said former away from said mandrel and finally discharging the finished shape from said movable element.

11. The method of transforming a length of 60 wire into a predetermined and finished wire shape 65 which consists in initially positioning said length in association with a support at right angle to a movable element adapted for axial movement toward and away from said support, thence moving forward said element toward said length and support whereby during said movement said element is caused to divert said length transversely to the path of travel of said element and fashion said length into final predetermined assemblance, 70 and finally welding certain meeting portions 75

thereof to hold the same in finished form concluding the forward movement of said element.

12. The method of transforming a length of wire into a predetermined and finished wire shape 5 which consists in initially positioning said length in association with a support at right angle to a movable element adapted for axial movement toward and away from said support, thence moving forward said element toward said length and support whereby during said movement said element is caused to divert said length transversely to the path of travel of said element and fashion said length into final predetermined assemblance, 10 thence reversing the travel of said element whereby said fashioned length is detached from said support, and finally welding certain meeting portions thereof to hold the same in finished form during said reverse travel of said element.

13. The method of transforming a length of wire 20 into a predetermined and finished wire shape which consists in initially positioning said length in association with a support at right angle to a movable element adapted for axial movement toward and away from said support, thence moving forward said element toward said length and support whereby during said movement said element is caused to divert said length transversely to the path of travel of said element and fashion said length into final predetermined assemblance, 25 thence reversing the travel of said element whereby said fashioned length is detached from said support by said element, thence welding certain meeting portions thereof during said reverse travel of said element to hold said fashioned length in finished form, and finally discharging 30 the finished shape from said element.

14. The method of transforming a length of wire 35 into a predetermined and finished wire shape which consists in initially positioning said length in association with a support, thence subjecting said length to the action of a movable element independent of said support comprising a series 40 of formers adapted upon movement axially toward said support by said element to divert portions of said length transversely to the path of travel of said formers whereby said length is fashioned to assume final predetermined assemblance and finally securing certain meeting portions 45 thereof to hold the same in finished form.

15. The method of transforming a length of wire 50 into a predetermined and finished wire shape which consists in initially positioning said length in association with a mandrel, thence subjecting said length to the action of a reciprocally acting element independent of said support comprising a series 55 of fixed formers adapted upon movement axially toward said mandrel by said element to divert portions of said length transversely to the path of travel of said formers whereby said length is fashioned to assume final predetermined assemblance and finally welding certain meeting portions 60 thereof to hold the same in finished form.

16. The method of transforming a length of wire 65 into a predetermined and finished wire shape which consists in initially positioning said length in association with an apertured support, thence subjecting said length to the action of a movable element independent of said support adapted for movement axially toward and away 70 therefrom, comprising a set of deflecting formers adapted upon movement of said element toward said support to contact and deflect said length therefrom, whereupon in the continued forward movement of said element said formers pass 75

- through said support and thereby define and maintain said length of wire in final predetermined assemblance, and finally securing certain meeting portions thereof to hold the same in finished form. 5
17. The method of transforming a length of wire into a predetermined and finished wire shape which consists in initially positioning said length in association with an apertured support, thence 10 subjecting said length to the action of a movable element independent of said support adapted for movement axially toward and away therefrom, comprising a set of deflecting formers adapted upon movement of said element toward said support to contact and deflect said length therefrom, whereupon in the continued forward movement of said element said formers pass successively through said support and thereby successively define and maintain said length of wire in final 15 predetermined assemblance, thence welding certain meeting portions thereof to hold the same in finished form, and finally discharging the finished shape from said support upon retraction of said movable element therefrom. 20
18. The method of transforming a length of wire into a predetermined and finished wire shape which consists in initially positioning said length in association with a support, thence subjecting said length to the action of a movable element 25 independent of said support comprising a series of formers adapted upon movement axially toward said support by said element to be caused to successively contact and deflect said length therefrom and thereby fashion and maintain the same about said support whereby to assume said length of wire in final predetermined assemblance, and finally securing certain meeting portions thereof to hold the same in finished form. 30
19. The method of transforming a length of wire into a predetermined and finished wire shape which consists in initially positioning said length in association with a mandrel, thence subjecting said length to the action of a reciprocally acting element independent of said mandrel comprising a series of fixed formers adapted upon movement axially toward said mandrel by said element to be caused to successively contact and deflect said length therefrom and thereby fashion and maintain the same about said mandrel whereby to assume said length of wire in final predetermined assemblance, and finally securing certain meeting portions thereof to hold the same in finished form. 35
20. The method of transforming a length of wire into a predetermined and finished wire shape which consists in initially positioning said length in association with a support, thence subjecting said length to the action of a movable element independent of said support comprising a plurality of formers, certain of which are initially functional with respect to said length, other of which are intermediately functional and the remainder of which are lastly functional, each adapted upon movement axially toward said support by said element to respectively and successively contact and deflect said length therefrom and thereby collectively fashion and maintain the same about said support whereby to assume said length of wire in final predetermined assemblance, and finally securing certain meeting portions thereof to retain the same in finished form. 40
21. The method of transforming a length of wire into a predetermined and finished wire shape 45
- which consists in initially positioning said length in association with a mandrel, thence subjecting said length to the action of a reciprocally acting element independent of said mandrel comprising a plurality of formers, certain of which are initially functional with respect to said length, other of which are intermediately functional and the remainder of which are lastly functional, each adapted upon movement axially toward said mandrel by said element to respectively and successively contact and deflect said length therefrom and thereby collectively fashion and maintain the same about said mandrel whereby to assume said length of wire in final predetermined assemblance, and finally welding certain meeting portions thereof to retain the same in finished form. 50
22. An apparatus of the class described comprising a wire length support, means for positioning a wire length in association with said support, forming means, means for causing said forming means and support to meet axially whereby said length is diverted transversely of said forming means and fashioned about said support to cause certain portions of said length to meet and means for securing said meeting portions whereby said length is fashioned in finished form. 55
23. An apparatus of the class described comprising a wire length support, means for positioning a wire length in association with said support, forming means, means for causing said forming means and support to meet axially whereby said length is diverted transversely of said forming means and fashioned about said support to cause certain portions of said length to meet, means for securing said meeting portions whereby said length is fashioned in finished form and means for discharging the finished form from said support. 60
24. An apparatus of the class described comprising a wire length support, means for positioning a wire length in association with said support, forming means, means for moving said forming means axially toward said support whereby during said movement said length is caused to be deflected transversely to the path of travel of said forming means and thereby shaped about said support, and welding means operative at the terminus of said forward movement of said forming means to weld certain portions of the shaped length. 65
25. An apparatus of the class described comprising a wire length support, means for positioning a wire length in association with said support, forming means, means for moving said forming means axially toward said support whereby during said movement said length is caused to be deflected transversely to the path of travel of said forming means and thereby shaped about said support, welding means operative at the terminus of said forward movement of said forming means to weld certain portions of the shaped length and means operative subsequent to the operation of said welding means for discharging the welded shape from said support. 70
26. An apparatus of the class described comprising a support, a mandrel on said support, a series of apertures in said support disposed about said mandrel, a movable element comprising a series of formers adapted for registration with said series of apertures and means for moving said element toward said support whereby said series of formers in said forward movement suc- 75

cessively pass through said apertures and embrace said mandrel.

27. An apparatus of the class described comprising a support, a mandrel on said support, a series of apertures in said support disposed about said mandrel, a movable element comprising a series of graduated formers adapted for successive registration with said series of apertures and means for moving said element toward said support whereby said series of formers in said forward movement successively pass through said apertures and collectively embrace said mandrel.

28. An apparatus of the class described comprising a stationary support, a mandrel on said support, a series of apertures in said support disposed about said mandrel, a movable element comprising a series of fixed graduated formers adapted for successive registration with said series of apertures, means for moving said element toward said support whereby said series of formers in said forward movement successively pass through said apertures and collectively embrace said mandrel and means for reversing the movement of said element whereby to dissociate said formers from said mandrel.

29. An apparatus of the class described comprising a support, a mandrel on said support, a series of apertures in said support disposed about said mandrel, a movable element comprising a series of graduated formers adapted for successive registration with said series of apertures, means for moving said element toward said support whereby said series of formers in said forward movement successively pass through said apertures and collectively embrace said mandrel, welding means associated with said element and means for actuating said welding means upon said formers collectively embracing said mandrel.

30. An apparatus of the class described comprising a support, a mandrel on said support, a series of apertures in said support disposed about said mandrel, a movable element comprising a series of graduated formers adapted for successive registration with said series of apertures, means for moving said element toward said support whereby said series of formers in said forward movement successively pass through said apertures and collectively embrace said mandrel, welding means associated with said element, means for actuating said welding means upon said formers collectively embracing said mandrel and means for reversing the movement of said element whereby to dissociate said formers from said mandrel.

31. An apparatus of the class described comprising a support, a mandrel on said support, a series of apertures in said support disposed about said mandrel, a wire length supply in association with said support, a movable element comprising a series of deflecting formers adapted for registration with said series of apertures, and means for moving said element toward said support whereby a wire length from said supply is disposed in association with said mandrel and in the path of forward travel of said formers and thereby deflected transversely of the travel of said formers in shaped relation about said mandrel.

32. An apparatus of the class described comprising a support, a mandrel on said support, a series of apertures in said support disposed about said mandrel, a wire length supply in association with said support, a movable element comprising a series of deflecting formers adapted for registration with said series of apertures, means for moving said element toward said support

whereby a wire length from said supply is disposed in association with said mandrel and in the path of forward travel of said formers and thereby deflected transversely of the travel of said formers in shaped relation about said mandrel and means operative at the terminus of the forward travel of said formers to secure the shaped length in finished form.

33. An apparatus of the class described comprising a support, a mandrel on said support, a series of apertures in said support disposed about said mandrel, a wire length supply in association with said support, a movable element comprising a series of deflecting formers adapted for registration with said series of apertures, means for moving said element toward said support whereby a wire length from said supply is disposed in association with said mandrel and in the path of forward travel of said formers and thereby deflected transversely of the travel of said formers in shaped relation about said mandrel, means operative at the terminus of the forward travel of said formers to secure the shaped length in finished form and means for discharging the shaped finished form from said mandrel.

34. An apparatus of the class described comprising a support, a mandrel on said support, a series of apertures in said support disposed about said mandrel, a wire length supply in association with said support, a movable element comprising a series of deflecting formers adapted for registration with said series of apertures, means for moving said element toward said support whereby a wire length from said supply is disposed in association with said mandrel and in the path of forward travel of said formers and thereby deflected transversely of the travel of said formers in shaped relation about said mandrel, means operative at the terminus of the forward travel of said formers to secure the shaped length in finished form and means for reversing the travel of said element whereby to dissociate said formers and shaped finished form from said mandrel.

35. The method of making wire garment hangers which consists in initially positioning a predetermined length of wire in association with a support, thence subjecting said length to the action of an element comprising a former adapted upon the axial meeting thereof with said support to cause said former to divert said length of wire transversely of said former into garment hanger formation comprising a formed body portion, a hook, and meeting portions of said formed wire length contiguously disposed between said body portion and said hook, and finally securing said meeting portions to maintain the shaped hanger in finished form.

36. The method of making wire garment hangers which consists in initially positioning a predetermined length of wire in association with a support, thence subjecting said length to the action of an element comprising a former adapted upon the axial meeting thereof with said support to cause said former to divert said length of wire transversely of said former into garment hanger formation comprising a formed body portion, a hook, and meeting portions of said formed wire length contiguously disposed between said body portion and said hook, and finally welding said meeting portions to maintain the shaped hanger in finished form.

37. The method of making wire garment hangers which consists in initially positioning a predetermined length of wire in association with

a support, thence subjecting said length to the action of an element comprising a former adapted upon the axial meeting thereof with said support to cause said former to divert said length of 5 wire transversely of said former into garment hanger formation comprising a formed body portion, a hook, and meeting portions of said formed wire length contiguously disposed between said body portion and said hook, thence welding said 10 meeting portions to maintain the shaped hanger in finished form and finally discharging the finished hanger from said support.

38. The method of making wire garment hangers which consists in initially positioning a 15 predetermined length of wire in association with a mandrel, thence subjecting said length to the action of a movable element comprising a former adapted upon movement axially towards said mandrel to divert said length of wire transversely 20 to the path of travel of said former whereby said length is fashioned into garment hanger formation comprising a formed body portion, a hook, and meeting portions of said formed wire length contiguously disposed between said body portion 25 and said hook, and finally welding said meeting portions to maintain the shaped hanger in finished form.

39. The method of making wire garment hangers which consists in initially positioning a 30 predetermined length of wire in association with a support, thence subjecting said length to the action of a movable element independent of said support comprising a series of formers adapted upon movement axially toward said support by 35 said element to divert portions of said length of wire transversely to the path of travel of said formers whereby said length is fashioned into garment hanger formation comprising a formed body portion, a hook, and meeting portions of 40 said formed wire length contiguously disposed between said body portion and said hook, and finally welding said meeting portions to maintain the shaped hanger in finished form.

40. The method of making wire garment hangers which consists in initially positioning a predetermined length of wire in association with an apertured support, thence subjecting said length to the action of a movable element independent of 5 said support adapted for movement axially toward and away therefrom, comprising a set of deflecting formers adapted upon movement of said element toward said support to contact and deflect said length therefrom, whereupon in the 10 continued forward movement of said element said formers pass through said support and thereby define and maintain said length of wire in garment hanger formation consisting of a formed body portion, a hook, and meeting portions of 15 said formed wire length contiguously disposed between said body portion and said hook, and finally welding said meeting portions to maintain the shaped hanger in finished form.

41. The method of making wire garment hangers which consists in initially positioning a predetermined length of wire in association with a support, thence subjecting said length to the action of a movable element independent of said support comprising a plurality of formers, certain 20 of which are initially functional with respect to said length, other of which are intermediately functional and the remainder of which are lastly functional, each adapted upon movement axially 25 toward said support by said element to respectively and successively contact and deflect said length of wire therefrom and thereby collectively fashion and maintain the same about said support whereby to assume said length of wire into 30 garment hanger formation comprising a formed body portion, a hook, and meeting portions of said formed wire length contiguously disposed between said body portion and said hook, and finally welding said meeting portions to maintain 35 the shaped hanger in finished form.

DURWARD K. HOPKINS.
